UNITED STATES PATENT OFFICE

165,734

COMBINED BOTTLE AND BOTTLE CAP

Murray M. Barton, Kansas City, Mo., assignor to
Injection Molding Company, Kansas City, Mo.,
a corporation of Missouri

Application April 12, 1951, Serial No. 14,810

Term of patent 14 years

(Cl. D58—26)

To all whom it may concern:

Be it known that I, Murray M. Barton, a citizen of the United States, residing at Kansas City, in the county of Jackson and State of Missouri, have invented a new, original, and ornamental Design for Combined Bottle and Bottle Cap, of which the following is a specification, reference being had to the accompanying drawing, forming a part hereof.

Fig. 1 is a side elevational view of a combined bottle and bottle cap, showing my new design.

Fig. 2 is a plan view thereof.

Fig. 3 is a horizontal section on the line 3—3 of Fig. 1.

Fig. 4 is a perspective view of the bottle, showing the cap removed therefrom.

The dominant feature of my design resides in the cap portion, which is shown in full lines.

I claim:

The ornamental design for a combined bottle and bottle cap, as shown and described.

MURRAY M. BARTON.
